UNITED STATES PATENT OFFICE.

THOMAS W. MURPHY AND WLADYSLAW CZARNECKI, OF PHILADELPHIA, PENNSYLVANIA.

SPRAY NOZZLE.

Application filed January 6, 1919. Serial No. 269,897.

To all whom it may concern:

Be it known that we, THOMAS W. MURPHY, a citizen of the United States; and WLADYSLAW CZARNECKI, a citizen of Poland, residing in Philadelphia, Pennsylvania, have invented Spray Nozzles, of which the following is a specification.

One object of our invention is to provide a substantial and inexpensive device for finely dividing liquids such as water, oil, acid, etc., when these are supplied under high pressure;—the various parts being of such design as to permit of their being easily and quickly cleaned usually without removal from their supply connections.

It is further desired to provide a spray nozzle which while having relatively large and therefore easily cleaned passages or channels, shall have these so disposed and formed that there shall be but a relatively small flow of liquid through them under given pressure conditions, the arrangement of parts being such as to deliver the liquid in the form of a wide angle spray or conical atomized sheet.

Another object of the invention is to provide a nozzle of such construction as to be particularly adapted for manufacture out of porcelain or stoneware in order that while being acid-proof, it shall at the same time be relatively inexpensive as well as durable.

These objects and other advantageous ends we attain as hereinafter set forth, reference being had to the accompanying drawings, in which,

Fig. 1 is a vertical section of a relatively simple form of spray nozzle constructed according to our invention;

Figs. 2 and 3 are respectively a vertical section, and a plan of the deflecting element forming part of the nozzle shown in Fig. 1;

In the above drawings 1 represents the end portion of a conduit which may be of lead, having internal threads for the reception of a cap or cover member 2. The cavity of this cap is cylindrical in form and has at one end a relatively restricted central outlet 3 whose outer portion is flared, the bottom or seating face of the cavity from which the outlet opens being preferably flat or plane.

Within the cavity is mounted a member 4 which may be comparatively loose or snug fitting, having one face flat for coaction with the flat face of the cavity and provided with a tail 5 projecting from its opposite face.

The member has at the center of its flat face a spherically curved cavity or depression 6 of somewhat larger diameter than the adjacent part of the outlet, and this cavity is entered in the present case substantially tangentially, by two or any other suitable number of passages or ports 7 formed in the flat face of the member at approximately opposite points and having their outer ends continued rearwardly along the sides of the member as indicated at 8 so that they open on its second face and communicate with the main part of the cap cavity. Liquid is thus free to flow from the interior of the cavity of the cap through these side passages 8 and the passages 7 into the central recess 6 and it is noted that the latter passages preferably enter recess at approximately opposite points thereof.

While the cap 2 as well as the member 4 may be made of any material which will suit them for a given work, we so design them that they may conveniently be made of porcelain or earthenware and in order to prevent leakage between such an earthenware cap 2 and the pipe 1, a gasket or washer 9 is mounted within the threaded end of said conduit in position to be engaged by the inner edge of the cap 2 when this has been screwed into position.

Under conditions of operation when a liquid such as water under pressure is supplied to the conduit 1, it enters the cap 2 and acts to yieldingly hold the flat face of the member against the flat face or end of the cap cavity with its recess 6 immediately adjacent and coaxial with the outlet passage 3, so that said member may be forcibly raised or moved away from said disc by suitable means when it is desired to clean the nozzle. The liquid then flows through the side passages 8 of the member and enters the recess 6 at comparatively opposite points thereof through the passages 7, so that it is given a rotary movement by reason of the relative positions of these latter channels. Since the recess 6 is immediately adjacent and in line with the inner end of the outlet passage 3, the liquid passes out through this latter with a rotary movement which when it is finally delivered from the flaring outer part of said passage, causes it to assume the general form of a conical sheet composed of atomized or finely divided particles. The fineness of the subdivision of the liquid may be varied by

altering the pressure at which it is supplied to the conduit 1 as well as by the relative proportion and disposition of the various channels 8, 7, 6 and 3.

5 If it be desired to increase the rate of delivery of the liquid from the nozzle or to cover the area which the spray strikes with approximate uniformity, we may provide a passage 10 extending axially through the 10 member and its tail, and this results in the delivery to the recess of the member of a jet which is there broken up by the centrifugal action of the jets from other ports. The liquid is then delivered from the outlet in the 15 form of an evenly divided spray striking approximately uniformly over the area upon which it is directed.

It is particularly to be noted that since the face of the member 4 in which the recess 20 5 and channels 7 are formed is flat as is also the end of the cap 2 with which this member coacts, it is possible to easily construct these parts of porcelain or stoneware even in relatively small sizes. The construction thus 25 lends itself particularly to the manufacture of nozzles for use in finely dividing or atomizing liquids having a corrosive or an erosive action, especially where such devices are exposed to the action of corrosive gases or liquids.

A vital feature of the invention resides in the ease with which the nozzle may be cleaned while in use without the necessity for taking it apart, since when liquid under 30 35 pressure is supplied to the conduit 1 the comparatively loose or snug-fitting member 4 is forced toward the outlet end of the cap 2, from which it may be raised by a wire or pin inserted through the outlet passage 3. The flow of liquid following this movement 40 of the member will dislodge any solid matter which may have partially or wholly stopped

the flow of liquid through the channels in the nozzle. When necessary, the interior of the nozzle may be opened for inspection and 45 cleaning by unscrewing the cap from the pipe and it is obviously of the simplest construction since it includes but three parts in addition to the gasket or washer 9.

From the foregoing description it will be 50 noted that our nozzle is inexpensive, is not likely to get out of order or easily clog, and may be easily cleaned by the insertion of a pin or the like through its outlet passage 3^a so as to raise the member 4 temporarily from 55 its seat and thereafter permit it to return thereto when said pin is removed by reason of the pressure exerted upon it by the liquid.

I claim:

1. The combination in a nozzle of a hollow porcelain cap having a flat inner surface and an outlet opening therefrom; with a loose porcelain member in the cap having a flat face normally engaging the flat face thereof and formed with a recess adjacent 65 the outlet opening, said member being freely movable toward and from said flat face of the cap and having passages leading to the recess.

2. The combination in a nozzle of a hollow cap having a flat inner surface and an outlet opening therefrom; with a loose member in the cap having a flat face normally engaging the flat inner surface thereof and formed with a recess adjacent the outlet 70 75 opening, said member being freely movable toward and from said outlet and having passages leading from the hollow of the cap to the recess, there being an axially placed passage extending through said member into 80 its recess.

In witness whereof we affix our signatures.

THOMAS W. MURPHY.

WLADYSLAW CZARNECKI.
